COLLAPSIBLE BOAT

Anton Horak, Chicago, Ill.

Application June 2, 1932. Serial No. 614,942

4 Claims. (Cl. 9—2)

This invention relates to a collapsible boat of sturdy construction, a preferred form of which is hereinafter described, and to novel means of attaching a flexible waterproof covering thereabout.

An object of my invention is the provision of a collapsible boat comprising a plurality of panels and novel means on said panels whereby the same may be quickly and economically assembled and connected together to form a sturdy boat structure and wherein a waterproof covering may be quickly and removably attached about the outside of the boat structure.

A further object of my invention is the provision of a collapsible boat which comprises a plurality of panels which have means thereon whereby the same may be assembled and connected together quickly to form a boat and which is rendered waterproof by attachment of a flexible waterproof material about the boat structure.

A further object of my invention is the provision of a collapsible boat comprising a plurality of substantially rectangular panels adapted to be removably connected together in the shape of a boat in combination with conveniently removable braces which absorb the transverse stresses, and wherein the side panels of the boat are so connected together and to the bottom panels of the boat that they withstand and absorb the longitudinal stresses.

A further object of my invention is the provision of a collapsible boat which comprises a plurality of connectible sections and which is adapted to be rendered waterproof by removably mounting thereabout a waterproof covering which is adapted to be partially held in place by the means which attach certain of said sections together.

On the drawings:

Fig. 1 is a top plan view of my invention showing the boat in assembled operative condition.

Fig. 2 is a cross sectional view longitudinally of the boat taken on line II—II of Fig. 1.

Fig. 3 is a perspective view of my boat in disassembled position adapted for convenient carriage and transportation.

Fig. 4 is a cross sectional view taken across the bow of the boat shown in Fig. 1.

Fig. 5 is a cross sectional view taken across the stern of the boat at a point in front of the diagonal braces.

Fig. 6 is an enlarged fragmentary view of the bow showing in dotted lines the shape of my canvas covering and the manner in which the same is folded.

Fig. 7 is a reduced perspective view showing the shape of my preferred form of boat and the relative position of the seats.

As shown on the drawings:

The reference numeral 10 indicates a plurality of side panels, preferably four in number, which are made of a good quality lumber or plywood and which are substantially of equal area and rectangular in shape as indicated. The reference numeral 11 indicates a similar rectangular panel 65 which is adapted to constitute the stern of my portable boat. Each of the side panels 10 and the stern panel 11 have relatively wide hinge straps 12 secured by rivets or the like on and along the entire ends of each panel, said hinge 70 straps terminating in knuckles which are so formed that when the panels are assembled in a manner shown in Fig. 2 they interfit so that the longitudinal apertures of the interfitting knuckles register for the convenient reception of a removable pintle 13 which is adapted to be inserted from the top. One of a plurality of pintles 14 is inserted in each of the interfitting adjacent straps and knuckles as indicated, and in the same manner, the stern panel 11 has like straps and knuckles 80 secured on its ends and is secured in substantially perpendicular position to ends of the rear-most side panels 10. The forward end of the two foremost panels are secured together by one of the pintles 14 as indicated in Figs. 1 and 6, and forms 85 a pointed bow of the boat structure.

A plurality of the bottom panels 15, which are preferably of wood and of substantially the same area as the side panels aforesaid, each carry on their opposite ends a pair of hinge straps 16 each 90 terminating in a knuckle, each of which knuckles are adapted to interengage with the knuckles of hinge straps 17 which are securely mounted on the inner surface of the side panels 10 a short distance from the lower edge thereof and in the 95 same spaced apart position as the hinge straps 16 on the bottom panels 15. In assembling the boat structure the bottom panels are mounted so that the apertures of the respective knuckles 16 and 17 register and each thereof receive one 100 of a plurality of short pins 17' shown in Fig. 5 in side elevation. The bottom panels 15 and the removable means therefor just described are preferably mounted in spaced apart relation 105 along the bottom of the boat as indicated in Figs. 1 and 2, certain of said panels 15 being mounted so that the ends thereof pass across the juncture of adjacent side panels and the respective interfitting straps and knuckles of such bottom panels are removably connected to adjacent panels, the 110

end of said panels thereby giving added rigidity to the boat structure to absorb transverse and diagonal stresses of the boat.

A pair of relatively short panels 18 having 5 end straps and knuckles 19 at each end thereof are adapted to be removably mounted respectively to a strap and knuckle 20 secured on a pair of side panels 10 of the boat and to a strap and knuckles 21 secured on one of the bottom panels 10 15. A removable pin is inserted in the apertures of the interfitting knuckles and each of said panels 18 forms a sturdy brace between the bottom and side panels, as clearly indicated in Figs. 5 and 2. In my preferred form I employ only 15 two of these braces which are preferably mounted to straddle the juncture of adjacent panels and thereby imparting rigidity to substantially the whole side of the boat.

As indicated in Figs. 2 and 4, to impart rigidity 20 to the foremost panels comprising the boat, I employ a block 22 which has on one face thereof perpendicularly extending metal knuckles shown in Fig. 4 which are adapted to be inserted in recesses formed in the knuckles of the hinge 25 straps 12, preferably at the upper end thereof, and so that the aperture of said knuckles will register with the apertures of the interfitting knuckles of the hinge straps 12 and will likewise receive the pintle 14, thereby holding the block 22 firmly against the inner surfaces of the adjoining panels 10.

A plurality of panels 23, preferably of wood 35 and of a length slightly longer than the normal width of the boat, are adapted to be inserted transversely within the boat between the opposite side panels 10, as indicated in Figs. 2 and 7, and each of which have a pair of downwardly extending brackets 24 secured on each end thereof, and are adapted to be removably mounted 40 in suitable eyelets (not shown) secured on the inner surface of the side panels 10 and are adapted to form seats at a height substantially midway between the bottom and upper edge of the side panels of the boat. The length of the 45 seat panels 23 being longer than the normal distance between the opposing side panels 10, I spread the opposite central and foremost side panels 10 apart to insert said seat panels, thereby imparting an outwardly flaring angle to the side 50 of the boat which is limited due to the action of the block 22.

After the boat structure is assembled as indicated in the foregoing, I mount a flat canvas or other waterproof fabric covering 25 about said boat by first placing the boat in the center thereof and bringing the edges of said canvas upwardly. A plurality of hook members 26 are secured along the edges of the waterproof covering 25 and are brought upwardly and certain of said members 60 26 hooked over the upper edge of the side panels 10. Certain of said hook members 26 have apertures therein and are positioned at such points so that they may be brought up to engage the upper ends of adjoining hinge straps 12, and the pintles 14 respectively are inserted through 65 said apertures and downwardly through the interfitting knuckles as indicated in Figs. 2, 4, and 5. The waterproof covering 25 is flat and the shape of the bow thereof is indicated in dotted 70 lines in Fig. 6, and the manner in which it is folded is indicated so that triangular portions thereof are folded within the outermost wall so that the same will be substantially flush and present no unnecessary external obstruction. 75 Likewise, in folding the rear corner of the cover-

ing to fasten it at the rear corner, said covering is folded in a manner similar to that illustrated in Fig. 6 so that the outermost covering wall is held substantially adjacent the side panels of the boat.

As indicated in Fig. 1, a pair of oar locks 28 are preferably securely mounted on opposite side panels 10 for the convenient reception of oar forks of well known construction.

In the foregoing I have described the manner 85 of assembly of my boat from the individual parts and the manner of disassembly will be readily apparent. When the various panels are quickly disconnected by removal of the respective pintles, pins, etc., the same may be packed adjacent each 90 other as indicated in Fig. 3, the brace panels 18 being adapted to be connected respectively to the ends of the outermost panels in the pack by insertion of the pintles in interengaging knuckles. A pair of straps 27 or the like may be passed 95 around the pack to provide more convenient carriage or transportation, and it will be apparent that likewise the canvas covering 25 may be folded and included in the compact package illustrated in Fig. 3.

I am aware that many changes may be made and numerous details of the invention and construction thereof may be varied through a wide range without departing from the principles of this invention, and I therefore do not desire to 100 limit the patent granted thereon otherwise than necessitated by the prior art.

I claim as my invention:

1. A portable boat comprising a plurality of 110 substantially rectangular panels adapted to form the sides, stern and bottom of the boat; hinge straps on said side panels terminating in interfitting knuckles mounted along the ends and lower edge of said side panels and on the ends of the stern and bottom panels, said panels being 115 adapted to be assembled by interengagement of the knuckles; pintles removably mounted in adjacent interfitting knuckles of the side, stern and bottom panels respectively; a plurality of diagonal braces comprising relatively short panels 120 terminating in straps and knuckles removably connecting the bottom and side panels respectively; a plurality of reinforcing blocks having intermediate perpendicularly extending knuckles 125 removably engaging a pintle which connects adjacent panels, said block normally lying adjacent the inner surface of adjacent panels; a plurality of panels adapted to form seats and removably connecting opposite side panels, and a flexible waterproof fabric covering adapted to be secured 130 about the outside of said boat and means on the edges of said covering whereby the same may be removably attached to said pintles and to the upper edge of the side panels.

2. A portable boat comprising a plurality of 135 substantially rectangular panels adapted to form the sides, stern and bottom of the boat, the side panels terminating in interfitting hinge knuckles along the ends and lower edge of said side and stern panels and on the ends of the bottom panels, said panels being adapted to be assembled 140 by interengagement of the knuckles; pintles removably mounted in adjacent interfitting knuckles of the side, stern and bottom panels respectively; a plurality of diagonal braces comprising 145 relatively short panels terminating in straps and knuckles removably connecting the bottom and side panels respectively; a plurality of reinforcing blocks having intermediate perpendicularly extending knuckles removably engaging a pintle 150

which connects adjacent panels, said block normally lying adjacent the inner surface of adjacent panels; a plurality of panels adapted to form seats and removably connecting opposite side panels, and a flexible waterproof fabric covering adapted to be secured about the outside of said boat.

3. In a collapsible boat, a plurality of side panels; a plurality of straps and knuckles on the panel edges, the hinge straps and knuckles of adjacent panels being adapted to interengage; a plurality of bottom panels forming the boat bottom; interfitting hinge knuckles on said bottom panels and on said side panels at the points of juncture thereof; a removable pintle in each pair of interengaging hinge knuckles, a plurality of panels removably connecting the side and bottom panels respectively to form diagonal braces; and a waterproof covering removably secured about the structure formed by said assembled panels, and oar locks secured on opposite side panels, said panels when, disassembled being adapted to be positioned adjacent each other in

different planes, the outer side panels and said brace panels being connectible to form an enclosing rectangular container for said package.

4. A portable boat having a skeleton comprising a plurality of substantially rectangular panels; removable interlocking means secured along two or more edges of each of said panels whereby said panels may be connected together to form the skeleton sides, stern and bottom; a plurality of braces removably connecting the bottom and sides of said boat; reinforcing blocks removably mounted across the juncture of adjacent panels; a plurality of panels removably connecting the sides of said skeleton at points intermediate the bottom and upper edges, said panels being adapted to form seats, and a flexible waterproof covering removably secured about said boat, said panels, when disassembled, being adapted to be superposed to form a rectangular package wherein in the said brace panels connect the two outermost panels to form a retaining package.
